OFFSET ROTOR VANE PUMP

William H. Curtis, Dayton, Ohio, assignor to
 Curtis Pump Company, Dayton, Ohio, a corpora-
 tion of Ohio

Application, March 8, 1939, Serial No. 260,570

8 Claims. (Cl. 103—138)

This invention relates to vane pumps of the offset rotor type wherein the bore of the cylinder is so formed that the ends of the vanes oscillate toward and away from the rotor axis as they are revolved therein by the rotor, and is particularly applicable to a structure wherein solid through vanes are used but may advantageously be employed in rotary pumps of the class having divided vanes.

An object of the invention is to construct a pump of this type having a cylinder with a bore so formed as to provide simultaneous working contact with opposite ends of the vanes at all times.

Another object is to provide a pump of this character having the cylinder bore so formed that the volume of fluid transferred from the low to the high pressure side of the pump will be substantially the same per unit of angular movement at all points of rotation of the shaft, whereby pulsationless discharge will be so nearly achieved as to satisfy most practical purposes.

Another object is to so form the interior curvature of the cylinder of a pump of this kind, that there will be no sharp changes in the oscillatory velocity of the vanes as their ends move over the cylinder wall, to the end that mechanical shock will be absent even at exceptionally high speeds.

In the art as known, substantially pulsationless discharge and mechanical smoothness have not been achieved in one and the same structure, due to the fact that attainment of the one imposes conditions which make it highly difficult to fulfill the other.

It is therefore another object of this invention to so design a pump of this type that mechanical and hydraulic smoothness are each substantially present, each without sacrificing the other.

Another object is to so form the cylinder bore curvature that the radius of curvature at any point is as near the rotor axis as possible whereby the pressure angle of the bore with the end of the blade will be kept at a minimum.

Another object is to so form and proportion the several curves comprising the cylinder bore, that resonable and practicable acceleration forces only need act upon the blades in their sliding motion through the rotor.

Further objects and advantages will appear as the invention is further described and appropriate reference is made to the drawings, wherein,

Fig. 1 is an axially transverse section through a rotary pump of the character hereinbefore dis-

cussed and having a cylinder bore curvature made up of two opposite circle arcs having their ends joined by opposite curves which take the form of an Archimedes spiral. The pump of Fig. 1 is no part of this invention and is shown only for comparison with the improved pump herein disclosed.

Fig. 2 is an outline of the cylinder bore which may be employed in the pump of Fig. 1, and which produces, when so employed a theoretical non pulsating delivery, but with the disadvantage that there is such pronounced mechanical shock that the device is wholly impracticable.

Fig. 3 shows a pair of circle arcs of different radii having common tangents at their point of juncture.

Fig. 4 shows the upper left quadrant of the bore of Fig. 2 to an enlarged scale together with a corrective curve which should replace the middle portion of the original curve of the quadrant if mechanical shock is to be eliminated.

Fig. 5 shows the complete outline of a cylinder bore which is employed in the pump of Fig. 6 and which has the corrective curve shown in Fig. 4 applied thereto, whereby substantially non pulsating delivery is achieved and mechanical shock prevented.

Fig. 6 is an axially-transverse section through a pump with the cylinder bore of Fig. 5 embodied, the section being taken at 6—6 of Fig. 7.

Fig. 7 is an axial section taken at 7—7 of Fig. 6 through the improved pump structure.

Fig. 8 is a side view of one of the vanes employed in the pump of Figs. 6 and 7.

Fig. 9 shows a vane with sealing members at the ends and for which, when employed, proper allowance must be made in the cylinder bore.

Figs. 10 to 13 show the manner of laying out the cylinder bore for several types of vane ends.

Referring now to Fig. 1, the body 11 of a rotary pump has a cylinder bore 12 against the upper side 14 of which the rotor 16 has bearing. The rotor 16 is rotatable on shaft 18 which has bearing in the hub 20.

The rotor 16 is provided with slots 22 at right angles to each other and with vanes 24 and 26 which are slidable radially in these slots. The vanes 24 and 26 are cut away at 28 to clear each other, the cut away portion being sufficient to permit the maximum radial movement of the vanes without interference with each other.

The vanes 24 and 26 are longer than the rotor diameter and consequently project radially beyond the rotor at one or the other end, the cylinder bore 12 being of such contour that the

vanes may be rotated therein by sliding back and forth in the rotor slots. For convenience in description, the center lines of the vanes are designated by letters CC_2 and C_1C_3 .

Interchangeable suction and discharge ports 27 and 29 are provided in the form of slots each extending circumferentially over one blade span and preferably having an axial width considerably less than the axial measurement of the rotor.

Since both ends of a vane must contact the cylinder bore at all points of rotation of the rotor, obviously the bore 12 may not be round, since $CC_2=C_1C_3=AG=BF$. The bore in fact comprises a sealing zone arc CAC_1 having the radius AO of the rotor, a diametrically opposite pumping zone arc C_2GC_3 having a radius OG equal to the rotor radius plus the excess of the vane length over the rotor diameter, and the two curves connecting the ends of the two said arcs being necessarily such as to pass through B and F respectively, and such as to contact both ends of a vane at any point of its rotation. The sealing and pumping zone arcs both have their center at O, the axis of the rotor.

Now since the fluid occupying the space 30 is bounded by two circle arcs having the same center, it follows that uniform rotation of a vane from C_3 to C_2 effects a uniform delivery of the fluid within the space 30 into the space 32, so that, if there are no other unbalancing effects, non pulsating delivery is fully achieved. It must be noted, however, that while one vane is passing from C_3 to C_2 , another is passing from C_2 to C_1 . The explanation of how this affects the volume in the space 32 follows.

If a vane could move from C_2 to C_1 without retracting into the rotor, the volume in space 32 would be neither increased nor decreased by such movement. The fact is, however, that while a vane passes from C_2 to C_1 , the extended blade portion 36 which projects from the rotor at C_2 retracts wholly into the rotor slot, thereby removing just that much metal out of space 32 which must be replaced by a volume of liquid equal to the volume of metal removed. It follows that the volume of fluid delivered from the discharge end 34 per quarter turn of the rotor is equal to the volume in the space 30 minus the volume of the part 36 of a blade. It has been shown by reference to Fig. 1 that movement of a fluid from space 30 to space 32 is constant when the rotor speed is constant, that is, if any one degree of rotor rotation transfers a given volume of fluid from the space 30 to the space 32, then every other degree of the ninety degrees rotation between C_3 and C_2 will transfer an equal volume.

It follows that, if the ultimate discharge from the end 32 is to be constant, the rate of retraction of the vane part 36 must also be constant, that is, any degree of rotation of the ninety degrees from C_2 to C_1 , must reduce the volume of the extended portion of a vane the same amount as any other degree.

To illustrate still further by a concrete example, suppose that each degree of rotation in the direction of the arrow 38 will cause the vane 24, by moving anti-clockwise away from C_3 , to transfer one cubic inch of liquid from the space 30 into the space 32, and that upon each degree of movement of the vane 24 from C_3 toward C_1 the volume of the blade portion remaining extended will have been decreased by one tenth cubic inch, then the discharge at 34 will be exactly nine tenths cubic inch for each and every degree of rotation of the rotor. The discharge rate will

then be theoretically constant and pulsationless discharge will be attained.

Now to satisfy the foregoing conditions mechanically the cylinder bore of the four vane pump shown in Fig. 1 must have a cross sectional contour such as is shown in Fig. 2. In this bore the arc CC_1 is drawn with the radius of the rotor from the center O. The arc C_2C_3 is drawn from the same center but with substantially longer radius. The curves C_1FC_2 and CBC_3 are duplicate constant extension or retraction curves, that is, Archimedes spirals, which cause a blade to retract the same amount in any one degree of rotation as in any other degree. The polar equation of the Archimedes spiral is $r=a\theta+c$, wherein r =polar ordinate, a =a constant, θ =angular distance in radians of r from the initial line, and c =a constant. The constants a and c are so selected as to cause the curve to pass through C and B as in Fig. 4, the lengths and locations of OC and OB having been previously ascertained from the required proportions of the particular pump under consideration.

With a bore such as is shown in Fig. 2 incorporated in the pump Fig. 1, and assuming a constant velocity of rotation, the velocity of retraction of the part 36 of a vane is exactly the same per unit of rotation throughout its movement from C_2 to C_1 . In such a pump, however, a vane, after moving from C_3 to C_2 without retraction, instantly changes at C_2 from zero rate of retraction to the maximum rate of retraction, and then without acceleration or deceleration maintains this constant rate of retraction from C_2 to C_1 , then at C_1 instantly changes from the maximum rate of retraction to a zero rate of retraction. Thus a vane would acquire all of its velocity of extension or retraction instantly as it crosses a point C, C_1 , C_2 , or C_3 , and the mathematical value of the acceleration forces acting upon the vane would be infinity.

Mathematical proof of the foregoing assertion may be made as follows:

$$r=a\theta+c$$

$$\frac{dr}{d\theta}=a$$

$$\frac{d^2r}{d\theta^2}=0$$

With uniform angular velocity of the rotor, θ , or time, may be substituted for θ whereby

$$\frac{dr}{dt}=a=\text{velocity of vane (retraction or extension)}$$

$\frac{d^2r}{dt^2}=0=\text{acceleration of vane (retraction or extension)}$, proving that there is no acceleration of the vane along the path of the curve CB. All of it must therefore have been acquired at the entrance to, or exit from, the curve.

Now it is axiomatic that unless the several curves making up the cross sectional contour of the cylinder bore of a pump of this character have common tangents at their points of junction, practical operation is impossible. The curve of Fig. 3, for instance, comprises two circle arcs ss_1 and s_1s_2 the first with center O and radius OW and the second with center O_1 and radius O_1W_1 . Obviously the tangent TT_1 is common to both curves, and obviously a vane such as is shown in Fig. 1 as 24 or 26 would pass from one to the other of these curves without mechanical shock.

In order to further illustrate the impracticability of a pump bore such as is shown in Fig. 2, the locations of tangents to the arcs and curves at their points of juncture are computed and indicated as shown thereon to prove that, in such a bore, common tangents do not exist. Referring to Fig. 2, the line MC_1 is the tangent to the arc CAC_1 at the point C_1 and NC_1 is the tangent to the curve C_1FC_2 at the same point. Also PC_2 is the tangent to the arc G_3GC_2 at the point C_2 and RC_2 is the tangent to the curve C_1FC_2 at the same point. It is clear that there are no tangents in common. It can be shown mathematically that it is impossible to develop an Archimedes spiral tangent to a circle arc where the pole of spiral is at the same point as the center of the arc, as it must be in this construction. To illustrate mathematically:

If ϕ is the angle between the tangent and the polar ordinate, then

$$\tan \phi = \frac{r}{\frac{dr}{d\theta}} = \infty$$

if it is common with the tangent to the circle arc at the same point. But, for the curve of the Archimedes spiral heretofore given as $r = a\theta + c$. θ at point C (inasmuch as OC is the initial line for the curve CB) equals zero, and $r = c$. Also

$$\frac{dr}{d\theta} \text{ equals } a$$

Therefore

$$\tan \phi = \frac{c}{a}$$

equals a finite value less than infinity. Therefore the curve cannot be made tangent to the circle arc. The Archimedes spiral, notwithstanding the uniform delivery which would accrue from its use cannot be employed without some modification or correction at the points C, C_1 , C_2 , and C_3 .

In my copending application Serial No. 204-108, filed April 25, 1938, now Patent No. 2,165,963, issued July 11, 1939, substantially the same illustrative discussion was employed as is herein presented, to show that the pump cylinder bore herein shown in Fig. 2, comprising two opposite circle arcs of equal angle and different radius, having their ends joined by curves of equal radial increase per unvarying increment of rotation, as in an Archimedes spiral, would provide a pump having a theoretically uniform discharge, but could not be practically employed because common tangents do not exist at the juncture points between the several curves comprising the bore.

In the copending application, supra, the pump herein shown as Fig. 1 with a bore as in Fig. 2, was explained, then dismissed as too impractical for further consideration, since no way was then known to modify the bore to adapt it to practical use.

However, a way has now been found whereby a bore of the class described may be modified by the introduction of a corrective curve of another order between the ends of the Archimedes spirals and the circle arcs of the bore, so that while theoretically pulsationless discharge will not be wholly attained, the approach to it is so close as to satisfy most practical requirements.

Fig. 4 is an enlarged view of a quadrant, as 75

AOB, Fig. 1, but with the introduction of another curve DE for correcting the defect at C. The most desirable form for this correcting curve is one that will impart constant acceleration throughout its length to a vane as the vane passes over it. (Acceleration is here spoken of in its algebraic sense, that is, it may be either plus or minus depending on the direction of rotation.) For, if the acceleration is constant throughout the length of this correcting curve, it will obviously have a minimum value, and the forces acting upon the vane will thereby be greatly reduced. The curve required to meet this situation is a parabolic spiral which for convenience may have the form,

$$r_1 = a_1\theta_1^2 + c$$

which has for its first derivative

20

$$\frac{dr_1}{d\theta_1} = 2a_1\theta_1$$

and for its second derivative

$$\frac{d^2r_1}{d\theta_1^2} = 2a_1$$

25

(c is a constant equal to AO in all equations. θ equals radians between position of r in the curve EB and its initial line OC. And θ_1 equals radians between r_1 in the curve DE and its initial line OD.)

30

The boundary conditions for this correcting curve require that its polar ordinate equal OD at D and OE at E. Also that it be tangent to the circle arc at D and to the curve EB at E. It is inherently tangent to the circle arc at D for,

35

$$\tan \phi = \frac{r_1}{\frac{dr_1}{d\theta_1}} = \frac{a_1\theta_1^2 + c}{2a_1\theta_1} = \frac{c}{\theta_1} = \infty$$

40

as θ_1 equals zero at this point.

Now $\tan \phi$ at E on the curve

45

$$EB = \frac{r}{\frac{dr}{d\theta}} = \frac{a\theta + c}{a}$$

and $\tan \phi$ at E on the curve

50

$$DE = \frac{r_1}{\frac{dr_1}{d\theta_1}} = \frac{a_1\theta_1^2 + c}{2a_1\theta_1}$$

therefore to meet the boundary conditions

55

$$\frac{a_1\theta_1^2 + c}{2a_1\theta_1} \text{ must equal } \frac{a\theta + c}{\theta}$$

also

$$2a_1\theta_1 \text{ must equal } a$$

since

60

$$a_1\theta_1^2 + c \text{ must equal } a\theta + c$$

and we may write

65

$$\frac{a_1\theta_1^2}{2a_1\theta_1} = \frac{a\theta}{a}$$

$\theta_1 = 20$ which shows that the point of tangency between curves DE and EB will be at point E at a distance from D equal to θ_1 radians which is twice the distance CE or θ radians. C, therefore lies midway in the correcting curve DE. The length of the correcting curve may therefore be varied to bring the acceleration forces acting upon the vane within the limits of good practice. Having selected its length in terms of radians, θ and θ_1 are automatically evaluated, and the

value of the constant a_1 can likewise be determined.

To summarize for Fig. 4.

AD is a circle arc with radius OA.

DE is a parabolic spiral with initial line OD and equation $r_1 = a_1 \theta^2 + c$.

EB is an Archimedes spiral with initial line OC and equation $r = a\theta + c$.

OB is one half the vane length.

OB minus OA represents one half the maximum blade extension as measured from the rotor.

Fig. 5 shows the outline of a complete bore formed in accordance with the foregoing calculations. The ordinates for the quadrant AOB only need be calculated. Quadrant GOF is then determined by extending these ordinates through O and laying out, or measuring thereon, a constant distance AG from the curve ADEB. In other words, if y equals the opposite ordinate for curve GD₁E₁F, and L equals the vane length, $y = L - r$ or $y = L - r_1$. The quadrant AOF is then laid out as a symmetrical reproduction of AOB, and the quadrant BOG a symmetrical reproduction of FOG.

Figs. 6 and 7 show a complete pump the body of which has a bore 39 of the outline shown in Fig. 5. This pump comprises a body 40 counterbored to receive the end closing head 42 which is held to the body by the screws 44. Hub 46 provides a rotative bearing for the rotor shaft 48.

The rotor which may be broadly designated by the numeral 50, comprises a disc 52 at the inner end of shaft 48 and a ring of larger diameter than the disc extending from the disc. The ring has a large central opening 53 extending all the way through the ring to the disc. The ring is cut through to the disc by two radial slots 54 extending at right angles to each other, whereby the remainder of the ring comprises four equal segmental lugs 56.

Two through vanes 58 are slidably fitted to the slots 54, the vanes being notched half way through at their middle as at 60 (see Fig. 8) the notches being of such length as will prevent interference of the vanes, one with the other, as they slide back and forth through the slots. The ends of the vanes have arcuate grooves 62 into which the seal bars 64 are rockably fitted. Fig. 11 shows the end of a vane 58 to an enlarged scale. Here the cylinder bore curve C₄EB passes exactly through the center of the radius r_3 of the rocker seal bar 64. The measurement between the centers of opposite rocker seal bars in the same vane is therefore $AG = BF$, the vane operating in this case exactly like a theoretical vane having zero thickness and a length BF. The cylinder bore Figs. 4 and 5 is therefore laid out for such a theoretical vane.

Interchangeable suction and discharge ports 66 and 68 are provided in the form of circumferentially extending slots having an axially extending width considerably less than the axial measurement of the rotor body (see Fig. 7), so as to leave ample bearing for the ends of the vanes as they pass over the ports. Rotation of the pump may be in either direction, but for purposes of description rotation may be in the direction of the arrow 70. This will make the space 72 the low pressure side and the space 74 the high pressure side of the pump.

The arc DAD₂, with which the rotor is in constant contact, comprises a sealing zone, while the arc D₁GD₃, having its center in the rotor axis, plus curves C₅D₁ and D₃C₇ comprise the pumping

zone. It should be noted that the sealing zone arc extends over less than a blade span by an amount equal to the corrective curve portions DC₄ and D₂C₈ while the pumping zone extends over an entire blade span. The volume pumped per quarter revolution of the rotor will therefore be the volume in the space 75 between two rotor blades, minus the volume of blade extension at C₅.

10 The shortening of the sealing zone is necessary for the reason that, with the bore shown, the blade is not fully retracted in the rotor at C₅ but must continue on to D₂ before full retraction has been effected. If the port ended at C₆, and rotation was in the direction of the arrow 70, the fluid in the small space 76 between the rotor body and the cylinder bore 39 would be trapped and forced through the sealing zone. Such a condition would result in a decided shock 20 and must therefore be avoided.

It will be recalled that the pump of Fig. 1, wherein the bore 12 comprises two circle arcs joined by Archimedes spirals, was shown to have theoretically uniform discharge, because every 25 unit of rotation of a vane through the pumping zone moved an equal volume of liquid, and every like unit of rotation of a blade over the discharge port retracted an equal volume of the blade extension into the rotor, but that this pump was 30 mechanically impracticable because the several curves comprising the bore 12 had not common tangents at their points of juncture.

It will also be recalled that the bore 39, Fig. 5, incorporated in the pump of Figs. 6 and 7, is 35 made up of two opposite circle arcs, two opposite Archimedes spirals midway of the circle arcs, and four parabolic spirals connecting the respective ends of the circle arcs and Archimedes spirals, and that common tangents exist at the 40 juncture of all of the curves of the bore.

Obviously substantial theoretical perfection is attained mechanically in the movement of the vanes 58 around the bore 39, and perfection is so nearly attained hydraulically as to meet most reasonable requirements, for instance, while a vane rotates uniformly from D₃ to D₁ over the circle arc portion of the pumping zone thereby transferring uniform volumes per unit of rotation from space 75 into space 74, another vane moves from E₁ to E₂ over the Archimedes spiral portion of the discharge zone thereby retracting an equal proportion of the total blade retraction per unit of rotation.

In the instant case, although not necessarily 55 always, the circle arc portion D₁GD₃ extends over two thirds of the pumping zone, while the Archimedes spiral portion extends over a corresponding two thirds of the discharge zone. In this two thirds of each quarter revolution, therefore, perfectly uniform discharge is attained.

In that portion between C₇ and D₃, the volume moved increases very slightly per unit of rotation and from D₁ to C₅ it decreases slightly per unit of rotation. Similarly from C₅ to E₁ there is a slight acceleration of blade retraction and from E₂ to C₆ slight deceleration of blade retraction. These slight deviations from uniformity are too small to be noticeable at conventional speeds.

Among the objects of the invention enumerated is the maintaining of a minimum pressure angle between vanes and bore surface. This pressure angle is the complement of the angle

between the center line of the vane and the tangent to the curve at the point of vane contact.

It is desirable to hold this pressure angle to as low a value as possible to prevent excessive thrust components being built up between vane, rotor slot and bore surface, a condition which would cause excessive wear.

Treating a vane as having no thickness, the tangent of this pressure angle is equal to the cotangent of ϕ which equals

$$\frac{dr}{d\theta} \text{ or } \frac{dr_1}{d\theta_1}$$

Following out this calculation it may be shown that the greatest pressure angle will fall at E. Obviously the pressure angle may be made less as the difference between the sealing zone radius and the pumping zone radius is made less. The amount of their difference determines the capacity of a pump of a given size, the greater the difference the greater the capacity.

It has been shown by reference to Figs. 6 and 11 that vane ends could be provided with rocker seal bars so made that a cylinder bore, Fig. 5, to be used therewith could be calculated for a vane of zero thickness and length BF. Fig. 10 shows a similar but less approved method of treating the vane end to achieve a similar result.

In Fig. 10, a vane 59_a is shown in the bore 39, Fig. 5, at E₂. If this vane is revolved 180 degrees to E₃ the curve of the bore will be angled with respect to the vane as at 39_a. The vane will have an actual length of E₂E₃, Fig. 6, that is, the same as the length of a theoretical vane of zero thickness and length BF, and will operate in the bore of Fig. 5.

The vane end, Fig. 10, is somewhat objectionable in that at E₂ the vane comes to a point 61. When this vane rotates in the bore of Fig. 5, while it is passing from D₂ to D₁, bearing of the vane end against the cylinder wall will be along the surface 63 and while it is passing from D₃ to D, the bearing will be along the surface 65, but while it is passing over the sealing and pumping zones, the point 61 only of the vane will bear on the cylinder wall. During this time, that the point 61 only bears on the cylinder wall, the vane is not being forced to retract into the rotor slot by pressure against the vane end.

The arrangement of Fig. 10, while it provides one means of avoiding the use of rocker seal bars on the vane ends, is not approved, since a better way to accomplish this result may be had by the arrangement shown in Fig. 12.

In Fig. 12, a radius r₄ is selected for the vane end which will leave the corner 67 well away from contact with a cylinder bore 69 when the vane end is passing over that part of the bore having the greatest pressure angle with the vane. A theoretical bore 39_b is then plotted by the equations given for plotting the bore 39, Fig. 5, this theoretical bore passing through the point o. The actual bore 69 is then determined by having the minimum distance from any point on the curve 39_b to the curve 69 equal to r₄.

When it is desired that maximum capacity for a given size pump be attained, and the difference between the sealing zone radius and the pumping zone radius is accordingly made considerable, and a relatively high blade pressure angle results, the ends 71, Fig. 11, of the blade may be cut away to

such an extent as to leave insufficient depth to the groove 62 to adequately support the rocker seal bar 64.

In such a case, the method illustrated in Figs. 5 and 13 should be followed. Here a theoretical bore 39_c, Fig. 13, is plotted to extend through the center K of the bar from which the rocker seal is made. This theoretical curve is developed from the equation given for the bore 39, Fig. 5. A uniform minimum distance 73 is then maintained between the theoretical bore 39_c and the actual bore 77. This same dimension 73 is added to a bar 64, Fig. 11, to provide the bar 78, Fig. 13, the outer surface of the bar at 80 being formed to the minimum radius of curvature of the bore. It will be seen that the rocker 78, Fig. 13, has more bearing in the end of the vane than the rocker 64, Fig. 11.

The improved bore 39, Fig. 5, is shown only as applied to a through vane pump, that is, two connected vanes in one rotor slot, and with slots spaced at right angles, but it will be understood that the bore may be applied with almost equal advantage to rotary pumps having a different number of rotor slots, or divided vanes, that is, two vanes per slot, either with the usual spring means for urging pairs of vanes in the same slot outwardly into contact with the bore, or otherwise kept against the bore.

30 In the embodiment shown, the pump body itself is bored to the improved outline 39, but obviously the pump body or casing may be provided with a separate cylinder, or liner having its inner periphery formed to the outline shown.

35 While one embodiment of the invention only is herein shown and described, it is obvious that considerable alteration in structure may be made without departing from the spirit of the invention as defined in the appended claims.

40 I claim:

1. In a pump of the offset rotor type, a cylinder having a bore, the cross section of which, taken at right angles to the axis is composed of one circle arc drawn from the rotor axis to a radius equal to the rotor radius, a second circle arc opposite the first drawn from the rotor axis to a larger radius, two opposite Archimedes spirals intermediate these said arcs, and four parabolic curves joining the ends of the arcs to the ends of the Archimedes spirals, the arcs and curves being so formed and arranged that there are common tangents at all points of juncture.

2. In an offset rotor sliding multiple vane pump, a cylinder having a bore, the normal cross sectional contour of which comprises a circle arc drawn from the axis of the rotor with a radius equal to that of the rotor, an opposite circle arc drawn also from the rotor axis but with larger radius, two opposite Archimedes spirals intermediate the said arcs, and four parabolic spirals joining the ends of the arcs to the ends of the Archimedes spirals, said arcs and curves all having common tangents at their points of juncture, the respective lengths of the arcs and curves being such that a given point of one parabolic spiral is spaced from the corresponding point of the next parabolic spiral a distance equal to one or more whole vane spans.

3. In an offset rotor sliding vane pump, a cylinder having a bore, the cross sectional outline of which comprises a circle arc drawn from the rotor axis with a radius equal to that of the rotor, an opposite circle arc drawn also from the rotor axis but of larger radius, two opposite spirals of uniform retraction intermediate the said arcs, and

four curves of uniform acceleration joining the ends of the arcs to the ends of the curves of uniform retraction, said arcs and curves all having common tangents at their points of juncture, said cylinder having opposite suction and discharge ports each of which extends from an end of the first circle arc over one of the curves of uniform acceleration, over one of the curves of uniform retraction and half way over the next curve of uniform acceleration.

4. In a pump of the offset rotor sliding vane type, a pump body having a somewhat cylindrical bore, a cross section of which, taken in a plane normal to the axis, is defined by two opposite concentric arcs of unequal radii, with vane extending and retracting curves joining the ends of the arcs, a cylindrical rotor having a diameter of twice the smaller of the two radii rotatably positioned with its axis at the center of the arcs, said rotor having radial vane slots, vanes slideable in said slots, the ends of the vanes being always in contact with said bore, the vane extending and retracting curves having a middle portion comprising a curve of uniform retraction and two end portions comprising curves of uniform acceleration, the several curves and arcs all having common tangents at their points of juncture.

5. In a pump of the offset rotor sliding multiple vane type, a pump body having a somewhat cylindrical bore, a cross section of which, taken in a plane normal to the axis, is defined by two opposite concentric arcs of unequal radii, with vane extending and retracting curves joining the ends of the arcs, a cylindrical rotor having a diameter of twice the smaller of the two radii rotatably positioned with its axis at the center of the arcs, said rotor having radial vane slots, vanes slideable in said slots, the ends of the vanes being always in contact with said bore, the vane extending and retracting curves having a middle portion so formed as to provide uniform extension or retraction of a vane per unit of rotation and two end portions so formed as to provide uniform acceleration or deceleration to a vane per unit of

rotation, the several curves and arcs all having common tangents at their points of juncture.

6. The structure defined in claim 5 wherein suction and discharge ports extend from an end 5 of the smaller arc over one of the portions which provide uniform acceleration or deceleration, over the portion which provides uniform extension or retraction and half way over the other portion which provides uniform acceleration or 10 deceleration.

7. In a rotary fluid handling device including a slotted offset rotor having a plurality of vanes radially slideable in said slots, a housing for said rotor having a bore of improved construction, said 15 bore being provided with two oppositely disposed cylindrical surfaces having a common axis but unequal radii, two oppositely disposed curved surfaces intermediate but not joining said cylindrical surfaces, each of said curved surfaces 20 being so constructed as to cause uniform sliding movement of a vane in its slot per unit of rotation of said rotor, and four other curved surfaces generated along parabolic spirals and joining the ends of said cylindrical surfaces to the ends of 25 said first two intermediate curved surfaces, there being common tangents at the points of juncture of all of said cylindrical and curved surfaces.

8. In a rotary fluid handling device including a slotted offset rotor having a plurality of vanes 30 radially slideable in said slots, a housing for said rotor having a bore of improved construction, said bore being provided with two oppositely disposed cylindrical surfaces having a common axis but unequal radii, two oppositely disposed curved 35 surfaces intermediate but not joining said cylindrical surfaces, each of said curved surfaces being generated along an Archimedes spiral, and four other curved surfaces generated along parabolic spirals and joining the ends of said cylindrical surfaces to the ends of said first two intermediate curved surfaces, there being common 40 tangents at the points of juncture of all of said cylindrical and curved surfaces.
